UNITED STATES PATENT OFFICE

MELCHIOR L. LUEBBEN, OF LOS ANGELES, CALIFORNIA, ASSIGNOR TO SUPER STROPPER MANUFACTURING COMPANY, OF LOS ANGELES, CALIFORNIA, A PARTNERSHIP COMPOSED OF M. L. LUEBBEN AND W. N. SMITH

STROPPER

Application filed June 9, 1927. Serial No. 197,534.

My invention relates to improvements in stroppers for safety-razor blades, and has for its object to provide a mechanism capable of being conveniently carried in the user's pocket, having a two-part outer case or housing, which parts are moved toward and from each other to actuate their contained stropping mechanism.

That stropping mechanism comprises a tilting blade-holder, and stropping disks with those faces the blade being stropped is given stropping contact by means of the blade-tilting mechanism.

Other features of my invention relate to the mechanism for detachably holding the blade in place, and the mechanism for reciprocating the blade-holder to cause its tilting action.

The two-part case serves to protect its contained stropping mechanism from injury and dampness, its two parts serving also as handles for the operative manipulation of the stropping mechanism.

The twin disks have opposed stropping faces, which faces may be either flat or convex. The disks strop the razor blade along its entire edge in a diagonal direction, the contact of the blade and the stropping disk being at all times of uniform pressure.

Each twin-disk member is mounted on a pinion-driven shaft, and the shafts are set slightly out of parallelism, to secure the proper angle of incidence between the blade and the stropping surfaces, to secure proper stropping contact and prevent the cutting of the stropping surface of the disk by the blade.

Drawings

In the drawings—

Fig. 1 is a plan view of the stropper of my invention with its telescopic case closed.

Fig. 2 is an end view of the same.

Fig. 3 is a plan view of the stropping mechanism, the telescopic case being shown in section.

Fig. 4 is a longitudinal view of the stropper in section taken on the line 4—4 of Fig. 3.

Fig. 5 is a bottom plan view of the stropping mechanism in extended position, with the casing removed.

Fig. 6 is a plan view of the end of the mechanism shown at the right hand of Fig. 5.

Fig. 7 is a transverse sectional view taken on the line 7—7 of Fig. 4.

Fig. 8 is a similar view taken on the line 8—8 of Fig. 3.

Fig. 9 is a detailed fragmental plan view of the blade-holding latch and adjacent mechanism.

Fig. 10 is a fragmental side view of the twin-disks, illustrating their angulation with reference to each other.

Description

As shown in the drawings, I employ the case A composed of the two telescopic sections 10 and 11.

Mounted within the case section 10 is a frame B wherein are mounted the twin stropping disks 13 and 14, said disks 13 and 14 being mounted upon shafts 15 and 16 which are provided respectively with pinions 17 and 18.

The frame C consists of a cross-head 19 fixed upon the double rack 20—20 with which racks 20—20 the pinions 17 and 18 mesh as shown in Fig. 5. A blade-holding bar 21 is tiltingly secured at one end to the lug 22 by means of its terminal prong 23, its opposite end being provided with a spirally-twisted tongue 24 which extends through the slot 25 in the cross-bar 27 (see Fig. 6). By means of the formation of the tongue 24, a tilting movement is given to the blade-holding bar 21, in the following manner.

The frame D is held in place within the case 11 by means of screws 26—26 and consists of a cross-bar 27 and the two semi-cylindrical side pieces 28—28; the cross-bar 27 being spaced from the inner faces of the end of the case 11 by means of spacing-tongues 29 (see Fig. 3).

The razor-blade E is secured in place upon the bar 21 by means of the bifurcated latch bar F, which is locked or released by means of the latch 31, contoured as shown in Fig. 4, and having a terminal tongue 32. A locking guard 33 is formed on the cross-head 19, and is cut away as indicated at 34 so as to permit the latch 31 to be opened to release the

latch bar F and blade E, only when the tongue 32 is in alignment with the cut-away portion 34, thus insuring that the blade E will only be removed or replaced when the blade is out of contact with the inner faces of the twin disks 13-14. The latch 31 is normally held in closed or locking position by means of the coiled spring 35, mounted as shown in Fig. 4.

10 The latch bar F is bifurcated as shown in Fig. 4, where its lower arm is indicated as 50 and upper arm as 30.

15 The latch bar F is pivoted at 51 to the blade-holding bar 21, and has a depending terminal 20 52 to which the spring 35 is attached as shown in Fig. 4. When the latch 31 is released by finger pressure of the operator on the tongue 32, the latch-bar F is thrown upward by the 25 spring 35 and clear of the case-section 10, the case-section 10 being cut away at 53 to permit the latch-bar F and razor-blade E to swing clear of the case A; when the arms 30 and 50 of the latch-bar F are sprung apart, permitting the blade E to be removed and, if desired, replaced by another blade.

Mode of operation

20 The blade E having been latched in position upon the bar 21, stropping is effected by reciprocating the case sections 10 and 11 into closed and extended position, tilting the blade E with each stroke, as indicated in Fig. 8, so that each side of each edge of the blade is alternately stropped against the inner faces 25 of the twin disks 13-14; these faces as shown in Fig. 8 are preferably convexed to provide a greatly increased contact of the razor-blade and the disk. These stropping faces of the disks 13-14 are covered with any suitable 40 stropping material.

25 The disks 13-14 are actuated by the engagement of their pinions 17 and 18 with the racks 20-20 (see Fig. 5), while the tilting of the blade holding bar 21 to accomplish alternating contact of the edges of the blade E with the upper and lower convexed inner faces of the disks 13-14 (see Fig. 8) is affected by the engagement of the spirally twisted tongue 24 with the slot 25 in the cross-bar 27 (see Fig. 6).

30 I have found it desirable to mount the shafts 15 and 16, as shown in Figs. 4 and 10, with a slight divergence with reference to the length of the stropper, although in parallel 55 planes with reference to the width of the stropper, as shown in Fig. 8. This slight angulation of said shafts 15 and 16 avoids any cutting of the stropping inner faces of the disks 13 and 14, which might otherwise occur.

35 The structure thus shown and described may be variously constructed as to its component parts without departure from my actual invention as defined in the appended claims.

60 I claim:

1. A stropper for safety razor blades comprising a two part casing, a two part frame within the casing, the elements of which are respectively carried by the elements of the casing, abrasive disks carried by one element of the frame, means carried by the other element of the frame for actuating said disks when the elements of the casing and frame are drawn apart and pushed together, a blade holder carried by one element of the frame and arranged between the abrasive disks, and means for oscillating said blade holder and a blade held thereby when the elements of the casing and frame are pulled apart and pushed together thereby to bring the respective edges of a blade against the disks. 70

2. A stropper for safety razor blades comprising a two part casing, a two part frame within the casing, the elements of which are respectively carried by the elements of the casing, abrasive disks carried by one element of the frame and having pinions, a rack carried by the other element of the frame and engaging the pinions for actuating said disks when the elements of the casing and frame are drawn apart and pushed together, a blade holder carried by one element of the frame and arranged between the abrasive disks, and means including a twisted plate and a cooperating slot in one of the frames for oscillating said blade holder and a blade held thereby when the elements of the casing and frame are pulled apart and pushed together thereby to bring the respective edges of a blade against the disks. 80

3. A stropper for safety razor blades comprising a sectional hollow casing, the elements of which are movable toward and away from each other in the same plane, a sectional frame within the casing and wholly enclosed thereby when the casing is closed, the sections of the frame being interfitting and slidable with respect to each other in the same plane, and attached and supported respectively by the sections of the casing, opposed sets of abrading disks carried by one element of the frame and having a pinion, means including a rack carried by the other element of the frame and engaging the pinions for rotating the sets of disks when the elements of the casing and frame are moved with respect to each other, a blade holder carried by one of said elements of the frame and operating between the sets of disks, and means including a twisted plate and cooperating slot in the frame for oscillating the blade holder and a blade carried thereby when the elements of the casing and frame are relatively shifted thereby to bring the respective edges of a blade against the disks. 90

4. A stropper for safety razor blades comprising a sectional hollow casing, the elements of which are movable toward and away from each other in the same plane, a sectional frame within the casing and wholly enclosed thereby when the casing is closed, the sections of the frame being interfitting and slidable with respect to each other in the same plane, and attached and supported respectively by the sections of the casing, opposed sets of abrading disks carried by one element of the frame and having a pinion, means including a rack carried by the other element of the frame and engaging the pinions for rotating the sets of disks when the elements of the casing and frame are moved with respect to each other, a blade holder carried by one of said elements of the frame and operating between the sets of disks, and means including a twisted plate and cooperating slot in the frame for oscillating the blade holder and a blade carried thereby when the elements of the casing and frame are relatively shifted thereby to bring the respective edges of a blade against the disks. 100

5. In testimony whereof I have hereunto affixed my signature.

MELCHIOR L. LUEBBEN.
